UNITED STATES PATENT OFFICE.

ZALAL GUZIK, OF NEW YORK, N. Y.

DESIGN FOR A HOLDER FOR NECKTIE-BANDS.

SPECIFICATION forming part of Design No. 34,127, dated February 26, 1901.

Application filed January 31, 1901. Serial No. 45,516. Term of patent 7 years.

To all whom it may concern:

Be it known that I, ZALAL GUZIK, a citizen of the United States, and a resident of the city of New York, borough of Manhattan, in the county and State of New York, have invented and produced a new and original Design for a Holder for Necktie-Bands, of which the following is a specification, reference being had to the accompanying drawings, forming a part thereof, in which—

Figure 1 is a perspective view of a holder for necktie-bands embodying the features of my design. Fig. 2 is a rear elevation of the holder, and Fig. 3 is a longitudinal section on the line 3 3 of Fig. 2.

The leading features of the design consist in the back plate A, the needle termination B at the bottom of the plate, and the sheath C at the front of the back plate at a point below the top of the back plate and above its lower end, whereby portions of the back plate

extend both above and below the sheath, in which extending portions of the back plate apertures appear.

The minor features of the design consist in the tapering shape of the back plate and corresponding shape of the sheath, which latter is curved or flared outwardly at top and bottom, together with the longitudinal groove D in the back plate.

Having thus described my invention, I claim as new and desire to secure by Letters Patent—

The design for a holder for necktie-bands herein shown and described.

In testimony whereof I have signed my name to this specification in the presence of two subscribing witnesses.

ZALAL GUZIK.
